UNITED STATES PATENT OFFICE.

GEORGE M. LUTHER, OF MILWAUKEE, WISCONSIN, ASSIGNOR TO LUTHER BROTHERS COMPANY, OF MILWAUKEE, WISCONSIN, A CORPORATION OF WISCONSIN.

MILK-TESTER.

SPECIFICATION forming part of Letters Patent No. 734,725, dated July 28, 1903.

Application filed April 7, 1902. Serial No. 101,627. (No model.)

To all whom it may concern:

Be it known that I, GEORGE M. LUTHER, a citizen of the United States, residing at Milwaukee, county of Milwaukee, and State of Wisconsin, have invented new and useful Improvements in Milk-Testers, of which the following is a specification.

My invention relates to improvements in milk-testers, and pertains especially to that class of machines known as the "Babcock testers." In most of the machines of this class the bottle-holding tubes are located above the driving-wheel. This causes the standard to vibrate and also compels the operator to stand in an awkward position, owing to the fact that the testing-tubes revolve in close proximity to his head. The machines heretofore constructed, in which it is sought to avoid this difficulty, have been found too expensive or cumbersome for commercial purposes.

The primary object of my invention is therefore to provide a simple and convenient form of machine, in which the bottle-holding tubes are located below the driving gear-wheel, in a position convenient for the insertion of the bottles and also in a position of great stability, the bottle-holding tubes being brought close to the base of the standard.

Other objects of the invention are to simplify the construction, expedite assembling the machines, and provide a machine which is light in weight and in which friction is reduced to a minimum by antifriction devices which do not materially increase the cost.

In the following description reference is had to the accompanying drawings, in which—

Figure 1 is a top view of a so-called "two-bottle" tester embodying my invention. Fig. 2 is a side view of the same. Fig. 3 is a detail view of the clamp of a four-bottle tester. Fig. 4 is a detail showing a form of construction by means of which ball-bearings may be employed without any alteration or separate work upon either the base or the bottle supporting thimble or bracket.

Like parts are identified by the same reference characters throughout the several views.

The base-casting 1 is provided with a socket 2, in which a rod 3 is adapted to fit. The upper end 4 of the rod 3 is bent at right

angles to its lower portion and forms a bearing for the drive-wheel 5, the lower end being secured in the base 1 by means of a set-screw 6. The drive-wheel 5 is provided with 55 teeth 7, projecting both laterally and peripherally, as best shown in Fig. 2, whereby said driving gear-wheel is adapted to mesh not only with spur-wheels in the same plane, but with gear-wheels occupying a plane at right 60 angles to the plane of the driving-wheel.

The bottle-supporting brackets comprise two clamping-plates 10 and 11, respectively. The upper plate 10 is fast on a sleeve 12, which is provided with a pinion 13, adapted 65 to mesh with the laterally-projecting portions of the gear-teeth 7. The lower clamping-plate 11 is secured to the clamping-plate 10 by means of bolts 14. The clamping-plate 10 is provided with notches 16, in which the 70 wires 17, which support the bottle-holders 18, are adapted to engage, whereby when said clamping-plates are secured together by the bolts 14 the wires 17 may be bound between the clamping-plates and prevented from lateral movement by engagement in said notches. The wires or rods 17, which support the bottle-holders, are bent at 20, Fig. 1, whereby the bottle-holders are made to stand at an angle to the radii of the standard. This not only 75 facilitates the insertion of the bottles, but also provides for holding the bottles in the best possible position for centrifugal action in separating the milk and cream, I having found that in a rotating body there is a tendency to 80 sag away from the line of the propelling force, so that the centrifugal outward pressure is principally exerted a little to the rear of the true radial lines.

In setting up the machine the sleeve 12, 90 with the clamps 10 and 11, and the bottle-holders supported thereby are adjusted in position upon the base, and the standard-rod 3 is then passed downwardly through the sleeve 12 and the bracket into the socket 2 95 of the base until the side teeth of the driving gear-wheel 5 are brought into mesh with the pinion 13, when the set-screw 6 is adjusted to bind the rod 3 in position. A key 25 is inserted through the rod 3 above the pinion 100 13 to prevent the pinion and sleeve 12 from moving upwardly on the rod when rotated.

For the purposes of a four-bottle tester I provide the clamping-plate 10 with transverse grooves or notches 26 in addition to the longitudinal grooves or notches 16, so that supporting bars or wires of the bottle-holder 5 may be inserted in the grooves 26 at right angles to those supported in the grooves 16, the bars in the grooves 26 resting upon the bars 17, which are engaged in the grooves 16, as shown in Fig. 3. To provide antifriction-bearings for the machine, I use a ball-bearing cup 27, interposed between the bracket 11 and the base 1 and having a central aperture through which the rod 3 passes. A washer 15 28 rests upon the balls 29, and the plate 11 bears upon the washer. As the standard-rod 3 will hold the ball-bearing cup in position, it is not necessary to groove the opposing faces of the base or bracket plate 11, but 20 merely to interpose the ball-bearing cup and balls between the opposing surfaces of these parts. The provision of simple means for locking the rod 3 in the base in any desired position of adjustment facilitates assembling 25 the machines, as the insertion of the operating-rod brings the driving gear-wheel into mesh with the pinion in any case, no machine-work being required for fitting. The use of the rod 3 as a standard and also as a 30 stud or bearing for the drive-wheel 5 is of great importance, in that it does away with the necessity of providing large castings and also dispenses with a large amount of shop-work which would be required to fit such 35 castings for the desired purpose.

Having thus described my invention, what I claim as new, and desire to secure by Letters Patent, is—

1. In a machine of the described class, the 40 combination of a base; a standard-rod adapted to be engaged in an opening in the base, and having its upper end bent to form a bearing for a driving-wheel; a sleeve, loose on the rod and supported thereby upon the base; 45 holders for the milk-receptacles supported from the sleeve; a driving gear-wheel on the upper end of the standard; and a pinion fast on the sleeve adapted to mesh with the driving-wheel when the standard-rod is properly 50 adjusted.

2. In a machine of the described class, the 55 combination of a base, a standard-rod adjustably mounted therein, and forming a bearing at its upper end for a driving gear-wheel; a sleeve rotatably mounted upon the rod; a driving gear-wheel and motion-transmitting connections between the same and said sleeve; and means, carried by the sleeve, for supporting the milk-receptacles.

60 3. In a machine of the described class, the combination of a base; a standard-rod adjustably mounted therein and forming a bear-

ing at its upper end for a driving gear-wheel; a sleeve rotatably mounted upon the rod; a driving gear-wheel and motion-transmitting connections between the same and said sleeve; and means, carried by the sleeve, for supporting the milk-receptacles; together with means for locking the standard-rod in the desired position of adjustment. 70

4. In a machine of the described class, the combination with a base; of a driving gear-wheel; a bearing-rod therefor, having an elbow and constituting a standard; means for adjustably securing said rod to the base; a 75 rotatable carrier having sleeve-bearings, through which the standard-rod passes to the base; a pinion on the carrier, arranged to mesh with the driving gear-wheel; and bottle-holders mounted on the carrier. 80

5. In a machine of the described class, the combination with a base; of a driving gear-wheel; a bearing-rod therefor, having an elbow and constituting a standard; means for adjustably securing said rod to the base; a 85 rotatable carrier having sleeve-bearings through which the standard-rod passes to the base; a pinion on the carrier, arranged to mesh with the driving gear-wheel; bottle-holders mounted on the carrier, and axially 90 disaligned with the standard.

6. In a machine of the described class, a bottle-supporting carrier, comprising a sleeve provided with a pinion, and a clamping-plate; a second clamping-plate having an 95 aperture corresponding with that of the sleeve; and bolts for securing the clamping-plates together, and bottle-holders provided with supporting-bars engaged between the clamping-plates, one of the plates being recessed for the partial reception of the supporting-bars of the bottle-holders, whereby 100 said bars, when inserted between the clamping-plates, are held against lateral movement. 105

7. In a machine of the described class, a bottle-supporting carrier, comprising a sleeve provided with a pinion and a clamping-plate; a second clamping-plate having an aperture corresponding with that of the sleeve; a base 110 having an aperture also corresponding with the sleeve; a ball-carrying ring interposed between the base and lower clamping-plate; and a standard-rod removably inserted through the sleeve, clamping-plates, ring, 115 and secured in the base, said rod being provided with a gear-wheel at its upper end, adapted to engage the pinion on the sleeve. 110

In testimony whereof I affix my signature in the presence of two witnesses.

GEORGE M. LUTHER.
